UNITED STATES PATENT OFFICE.

ROBERT SANFORD RILEY, OF WORCESTER, MASSACHUSETTS, ASSIGNOR TO SANFORD RILEY STOKER CO., OF WORCESTER, MASSACHUSETTS, A CORPORATION OF MASSACHUSETTS.

UNDERFEED STOKER.

Application filed August 4, 1919. Serial No. 315,166.

To all whom it may concern:

Be it known that I, ROBERT SANFORD RILEY, a citizen of the United States, residing at Worcester, in the county of Worcester and State of Massachusetts, have invented a new and useful Underfeed Stoker, of which the following is a specification.

This invention relates to a stoker of the underfeed type, and particularly to improved devices for distributing the fuel laterally over the fuel bed.

It is the general object of my invention to provide an improved stoker of the type in which lateral retorts receive fuel from the usual longitudinal retort, and in which special provision is made for reciprocating such retorts or portions thereof to assist the lateral feed.

In the preferred form of my invention I provide means by which the different parts of each lateral retort may be laterally reciprocated in opposite directions.

My invention further relates to arrangements and combinations of parts to be hereinafter described and more particularly pointed out in the appended claims.

A preferred form of my invention is shown in the drawings in which

Fig. 1 is a plan view of my improved stoker;

Fig. 2 is a longitudinal sectional elevation thereof, taken along the line 2—2 in Fig. 1;

Fig. 3 is a partial front elevation;

Fig. 4 is a partial transverse sectional elevation, taken along the line 4—4 in Fig. 1;

Figs. 5 and 6 are detail sectional elevations taken along the lines 5—5 and 6—6 in Fig. 4;

Fig. 7 is a transverse sectional elevation, showing a different arrangement of the driving mechanism, and

Figs. 8 and 9 are views similar to Figs. 1 and 2 showing an additional modification in mode of operation.

Referring to the drawings I have shown an underfeed stoker in which coal or other fuel is fed from a hopper 10 to a longitudinal retort 11 by a reciprocating plunger or ram 12. The longitudinal retort 11 communicates with a plurality of lateral or branch retorts 13, in which the greater part of the actual combustion occurs.

Each lateral retort is commonly provided with an outer overfeed grate section 13^a and with a dumping or discharge plate 14 by

which the refuse is ejected, to fall into the usual ash-pit. Each lateral retort 13 is preferably formed in two sections, the retort being divided along the center line of the bottom of the retort and adjacent retorts being separated along the center line of the top of the side walls. Each of the retort sections thus formed is adapted to be reciprocated horizontally laterally by mechanism to be described. The division along the top of the side walls may be omitted when desired.

A plate 15 (Fig. 4) forms the bottom of the longitudinal retort and is provided with an upward projection 16 at its front end by which it is connected for reciprocation with the plunger 12. Lugs or projections 17 formed on the plate 15 assist in moving the coal rearwardly along the retort 11.

The plate 15 is supported on cross frame members 18 and is guided by angle plates 19 secured to said frame members. Cover strips 20 prevent the escape of coal along the sides of the plate 15 and an additional cover plate 21 (Fig. 2) prevents the accumulation of coal at the rear end of the plate 15.

Each half section of a lateral retort 13 may be formed as a single casting 22 upon which side grate blocks 23 and also the outer overfeed grates 13^a are mounted. An additional inner grate member 24 may be also secured thereto, which member forms the upper part of a side wall of the longitudinal retort and also the upper part of a side wall of the lateral retort.

The dumping plates 14 are formed in short sections corresponding to the lateral retort sections and are pivotally connected thereto at 25. These dumping plates are supported at their lower ends by rack bars 26 which may be manually moved in or out by pinions 27 engaging the teeth on said rack bars. The rate of discharge of the dumping plates is determined largely by the position of the rack bars 26.

The retort section castings 22 are mounted to slide laterally upon T-shaped supports 28 which may be integral with the frame members 18 previously described. These supports 28 are shown in the drawings as resting upon rigid I-beams 29.

It is customary in underfeed stokers to supply air under pressure to the chamber beneath the retort, from which the air passes upwardly through openings in the retort

2
side walls, thus increasing the combustion and cooling the walls. It is sometimes desirable to supply air at a lower pressure to the overfeed grates 23 and 13^a and for this purpose I provide each retort casting 22 with an intermediate partition 30 connecting through openings 31 and 32 with a chamber 33. The admission of air from the main air chamber to the chambers 33 is controlled by dampers 34 which may be manually adjusted.

The mechanism for longitudinally reciprocating the plunger 12 and retort bottom 15 and for laterally reciprocating the side retort sections may be of any suitable type, and as shown herein comprises a cylinder 35 within which is mounted a piston 36 connected to a piston rod 37 supported in bearings at the front of the stoker. A bell crank 38 has its forked end 39 received between collars 40 and 41 on the piston rod 37, and has its opposite end 42 connected by a link 43 to the plunger 12. Reciprocation of the piston rod 37 is effective through the connections described to reciprocate the plunger 12. Obviously the rod 37 may be extended to operate a series of stokers and may be reciprocated by mechanical devices if preferred.

30 A lever 44 (Fig. 3) is mounted on a fixed pivot 45 and has its upper forked end 46 positioned between collars 47 and 48 on the piston rod 37. The lower end of the lever 44 is connected by a link 49 to an arm 50 depending from a cam shaft 51 (Fig. 2) which in turn is provided with a plurality of oppositely disposed cams 52 and 53. The depending cams 52 engage lower faces 54 on brackets 55 integral with or secured to the alternate retort section castings 22, and the upwardly extending cams 53 engage upper faces 56 on the brackets 55 of the remaining sections. Through these connections the reciprocation of the piston rod 37 causes lateral reciprocation of the side retorts 13, all adjacent retort sections being commonly simultaneously reciprocated in opposite directions. The fuel bed is thus thoroughly agitated and the fuel is fed gradually over 50 the outer grates 13^a to the dumping plates 14 from which the refuse is discharged.

In order to avoid having incomplete lateral retorts at the ends of the stoker, I provide a plate 60 to fill in the space between 55 the top of the side wall of the first complete lateral retort and the end wall of the furnace and I provide a similar plate for the opposite end of the furnace. These plates are commonly provided with dumping or 60 discharge plates 14 and are preferably reciprocated laterally the same as the retort sections.

The operating mechanism above described provides for alternately reciprocating all adjacent retort sections, each section comprising

ing one half of a lateral retort and one half of an adjacent side wall. It is found desirable under certain conditions to reciprocate the two adjacent sections forming a retort wall together instead of alternately. 70

In Fig. 7, I have shown a double cam 61 adapted to engage an upper bracket 62 secured, for instance, to the retort section B, and a lower bracket 63 secured to the section B'. As the shaft 51 is oscillated, the sections B and B' will alternately approach and recede from each other.

By suitable selection and arrangement of the single cams 52 and 53, previously described, and the double cams 61, any desired relative movement of the retort sections can be secured. By using double cams throughout, each successive pair of retort sections may be caused to approach and recede and the successive pairs may each move in different directions. By using single cams 52 or 53 and the connections shown in Fig. 4 for each alternate pair of retort sections and using double cams 61 with the connections shown in Fig. 7 for the remaining pairs of retort sections, the following operation of the parts may be achieved, the construction being shown in Figs. 8 and 9. The plate A (Fig. 1) and the lateral retort section A' may be reciprocated as a unit by the mechanism shown in Fig. 4, their inner faces being at a constant distance apart. The retort section B may be reciprocated simultaneously and in the same direction as the plate A and the retort section B' may at the same time be reciprocated in the opposite direction by the mechanism shown in Fig. 7, the parts B and B' alternately approaching and receding from each other. The retort sections C and C' may be moved in the same direction as the section B', these parts remaining at a constant distance apart and being actuated by the mechanism of Fig. 4. 100

With this arrangement, the plate A and section B moving together form in effect a plunger, acting to push the fuel along the lateral retort formed by the sections A' and B'. In the same way, the sections B' and C' act together to feed fuel into the lateral retort formed by the sections B and C. 110

It will also be noted that the two sections forming each lateral retort or trough move in opposite directions to thoroughly agitate the fuel.

This arrangement possesses certain advantages in respect to fuel distribution over the arrangement first described, in which adjacent retort sections move in different directions simultaneously.

Furnaces of this type are particularly adapted for use in places where the headroom or space beneath the boilers is limited. The relatively short inclines of the lateral overfeed grates require much less space vertically than the long single incline of the 120

usual parallel retort stoker in which the discharge is at the rear end.

Having thus described my invention it will be evident that changes and modifications can be made therein by those skilled in the art within the scope of my invention as set forth in the claims, and I do not wish to be otherwise limited to the details herein disclosed, but what I claim is:—

10 1. An underfeed stoker comprising a longitudinal retort, means to feed coal to said retort, a plurality of lateral retorts communicating with said longitudinal retort and each formed in a plurality of parts extending in the direction of the retort length, and means to move said lateral retort parts to assist lateral movement of the fuel.

2. An underfeed stoker comprising a longitudinal retort, means to feed coal to said retort, a plurality of lateral retorts communicating with said longitudinal retort, each lateral retort being separated into two parts in the direction of its length, and means to reciprocate adjacent parts of adjacent retorts simultaneously in opposite directions.

3. An underfeed stoker comprising a longitudinal retort, means to feed coal to said retort, a plurality of lateral retorts communicating with said longitudinal retort and each formed in two parts, and means to reciprocate the two parts of each lateral retort in opposite directions.

4. An underfeed stoker comprising a longitudinal retort, means to feed coal to said retort, a plurality of lateral retorts communicating with said longitudinal retort and each having separate retort side wall sections, and means to reciprocate adjacent side wall sections simultaneously in opposite directions.

5. An underfeed stoker comprising a longitudinal retort, means to feed coal to said retort, a plurality of lateral retorts communicating with said longitudinal retort and each divided into separate parts at the center of the bottom thereof, adjacent lateral retorts having dividing walls separated at the middle of the top thereof to form independent side wall sections for said adjacent retorts, and means to reciprocate as a unit each of said side wall sections and that part of a retort bottom associated therewith.

6. An underfeed stoker comprising a longitudinal retort, means to feed coal to said retort, a plurality of lateral retorts communicating with said longitudinal retort and each divided into separate parts at the center of the bottom thereof, adjacent lateral retorts having dividing walls each separated at the middle of the top thereof to form independent side wall sections for said adjacent retorts, and means to reciprocate the two parts of each retort simultaneously in opposite directions.

7. An underfeed stoker having, in combination, a longitudinal retort, means to feed coal to said retort, a plurality of lateral retorts communicating with said longitudinal retort and formed in parts, discharge 70 plate sections connected with said lateral retort parts, and means to reciprocate said lateral retort parts and associated discharge plate sections to assist lateral movement of the fuel. 75

8. An underfeed stoker comprising a longitudinal retort, means to feed coal to said retort, a plurality of lateral retorts communicating with said longitudinal retort and formed in parts, means to reciprocate 80 adjacent lateral retort parts in opposite directions, and means to supply air at different pressures to said longitudinal and lateral retorts.

9. An underfeed stoker having, in combination, a longitudinal retort, means to feed coal to said retort, a plurality of lateral retorts communicating with said longitudinal retort and disposed on opposite sides thereof, each lateral retort being 90 formed of two separate castings, laterally opposite castings being joined in pairs, and means to oppositely reciprocate adjacent pairs. 95

10. An underfeed stoker having, in combination, a longitudinal retort, means to feed coal to said retort, a plurality of lateral retorts communicating with said longitudinal retorts and each formed in sections, said lateral retorts having raised dividing 100 walls intervening between adjacent retorts, an outer longitudinally extended overfeed grate mounted on each lateral retort section, and means to reciprocate said lateral retort sections to assist lateral fuel feed. 105

11. An underfeed stoker having, in combination, a longitudinal retort, means to feed coal to said retort, a plurality of lateral retorts communicating with said longitudinal retort and each formed in sections, said 110 lateral retorts having raised dividing walls intervening between adjacent retorts, an overfeed grate and a discharge plate mounted at the outer end of each lateral retort section, and means to laterally reciprocate 115 each lateral retort section and the parts associated therewith.

12. An underfeed stoker having, in combination, a longitudinal retort, means to feed coal thereto, a plurality of lateral retorts 120 communicating with said longitudinal retort and formed in parts, means to move the parts of said lateral retorts transversely of the stoker, a plate adjacent one of said lateral retorts, and means to move said plate 125 laterally.

In testimony whereof I have hereunto affixed my signature.

ROBERT SANFORD RILEY.
